UNITED STATES PATENT OFFICE.

EDWARD HEIM, OF PITTSBURG, PENNSYLVANIA.

IMPROVED WASHING-MACHINE.

Specification forming part of Letters Patent No. 97,917, dated December 14, 1869.

To all whom it may concern:

Be it known that I, EDWARD HEIM, of Pittsburg, in the county of Allegheny and State of Pennsylvania, have invented a new and Improved Washing-Machine; and I do hereby declare that the following is a full, clear, and exact description thereof, which will enable others skilled in the art to make and use the same, reference being had to the accompanying drawings, forming part of this specification, in which—

Figure 1 represents a vertical section of my improved washing-machine. Fig. 2 is a detail side view, partly in section, of the upper part of the same. Fig. 3 is a horizontal section of the same. Fig. 4 is a horizontal section of the sliding rod.

Similar letters of reference indicate corresponding parts.

This invention relates to a new machine for washing clothes; and consists in the introduction of several improvements whereby the machine is adapted to thoroughly clean coarse as well as fine articles without injury to the same, and in a comparatively short time.

A in the drawing represents the suds-box of the machine. It is made in form of a slightly conical or cylindrical tub, and is supported by legs B, or otherwise, in a vertical position.

C is the lid of the box. It is hinged so that it can be readily opened and closed, and can be held closed by a spring-catch, a, of suitable kind. A strip, b, of rubber, is fastened to the under side of the lid, where the same rests upon the edge of the box to close the same steam-tight.

D are corrugated or rounded ribs, arranged in vertical or inclined positions, or spirally along the inner side of the box A. E is a false bottom for the suds-box. It is perforated, and carries on its upper face a series of ribs, c c, which radiate from the center, as shown. Blocks or bars d hold the false bottom elevated above the main bottom e of the box. The false bottom rests loose upon the main bottom, and can revolve on the same.

Through the center of the cover C is fitted a vertical prismatic bar, F, which carries at its lower end a disk, G, of about the same diameter as the false bottom E. On the under side of the disk G are also formed ribs f f, radiating from the center, similar to those on the

surface of the false bottom. The ribs f carry on their sides plates of india-rubber, which project below them, as at g, or which may be bent over and around the edges of such ribs, as at h, to have both sides secured to opposite sides of each rib. The rubber plates are secured to the ribs by means of outer metal or wood plates i and suitable nails or pins j. The ribs of the false bottom may, if desired, also be provided with such rubber plates or coverings. Instead of setting the ribs radially, as described, they may be arranged in any other suitable manner upon the faces of the two disks.

The rod or bar F is prismatic, or of other non-cylindrical form. It is fitted through a bevel-gear wheel, H, which is, with its shank k, swiveled into the cover C of the suds-box. The wheel H meshes into the teeth of another wheel, I, which is hung in a frame, J, supported on the cover C. The wheel I has a projecting handle, L, by means of which it can be oscillated, or it may on its shaft have a crank to receive rotary motion. The frame J has an arm, l, which embraces a sleeve, m, through which the bar F is fitted. The sleeve is swiveled in the arm l, so that it can revolve, but not move up and down in the same.

M is a loose collar fitted around the bar F above the wheel H, and held down upon the said wheel H by a spring, N. In the collar M is a sliding pin, n, which is by a spring, o, forced against the bar F and through apertures of the same, as shown in Fig. 1.

When the articles to be washed have been placed upon the false bottom, the box is closed and the plate G let down upon the wash. The pin n is then allowed to spring into the bar F and to lock the same in the desired position. For coarse articles the disk G is forced further down to obtain greater pressure. For fine, delicate articles, it is more elevated. In either position it can be locked by the pin n. The wheel I is now revolved or oscillated, and imparts the same motion by the wheel H to the bar F and disk G. The rubber covered or lined ribs of the disk will gently rub the wash and carry it along on the false bottom. The latter aids in washing, but prevents the tearing of the goods, as under great strain it will revolve with the wash. The ribs D also serve to clean the articles, keeping them at

times stationary, while the disk revolves or swings. The sand and other heavy impurities fall through the perforated false bottom to the bottoms of the tub. When the process of washing has been completed the pin *n* is drawn out, and the bar *F* elevated, to raise also the disk *G*. The cover is then opened, and swings the rod *F* and disk *G* out of the way, permitting the ready removal of the articles, and the cleaning or refilling of the box.

If, during the washing process, strain is brought against the under side of the disk *G* by extra thicknesses of goods, such strain is taken up by the spring *N*, which permits the disk with the bar *F* to rise, and which also applies the requisite pressure to the articles while they are being washed.

Having thus described my invention, I claim as new and desire to secure by Letters Patent—

1. The suds-tub *A*, having steam-tight cover *C*, vertical corrugations *D*, and perforated and ribbed false bottom *E*, all constructed as described, in combination with the disk *G*, ribbed with rubber, in the manner set forth.

2. The improved mechanism for operating the disk *G*, consisting of bar *F*, gears *H* *I*, handle *L*, and spring-collar *M* *N*, all constructed, combined, and arranged as set forth.

EDWARD HEIM.
